UNITED STATES PATENT OFFICE.

JOHN WILLIAM PORTER, OF WILLIAMSTOWN, VICTORIA, AUSTRALIA.

APPARATUS FOR OPERATING MOVING TARGETS.

SPECIFICATION forming part of Letters Patent No. 724,330, dated March 31, 1903.

Application filed December 15, 1902. Serial No. 135,331. (No model.)

To all whom it may concern:-

Be it known that I, JOHN WILLIAM PORTER, ranger, a subject of the King of Great Britain, residing at the Rifle Ranges, Williamstown, 5 in the State of Victoria and Commonwealth of Australia, have invented Improved Apparatus for Operating Moving Targets on Miniature Ranges, of which the following is a specification.

10 Rifle practice with miniature ammunition has recently come into much favor on account of the facility of obtaining and convenience of ranges for such purposes, while its instructional value in the training of troops at 15 an insignificant expense and its interest as a pastime to the non-professional render the provision of a simple and efficient means for operating moving targets on such ranges of the highest importance.

20 This invention has been devised for the purpose of attaining that object, and the apparatus, briefly stated, comprises a traveler running to and fro on a pair of rails continuously and carrying a rotatable target adapted 25 to be rotated at irregular intervals through an angle of ninety degrees, so as to turn the same "edge on" and "face on" alternately, thereby effecting an irregularly-intermittent disappearance and reappearance of a moving 30 target.

The accompanying drawings illustrate my improved apparatus.

Figure 1 is a plan thereof; Fig. 2, an enlarged plan of the under side of the traveler, and Fig. 3 an enlarged end elevation of said traveler. Fig. 4 is a fragmentary perspective sketch illustrating grip on said traveler. Figs. 5 and 6 are enlarged perspective views of the spring-operated arm and tappet-wheel, respectively, illustrated in Fig. 2. Fig. 7 is a fragmentary plan illustrating a modification.

A represents a pair of horizontal rails upon which the traveler or carrier B runs continuously to and fro, being operated by the endless draft wire or cord C, to which it is attached by means of a pivoted rotatable arm D. Motion is imparted to the wire from a convenient motor E, such as a spring self-winding clockwork-escapement driven by a 45 suspended weight.

The target F is mounted on a vertical spindle G, having bearings in the traveler B, and

upon said spindle is a tappet-wheel having four equidistant radial projections H, adapted to strike against pins J, projecting from a rotatable rod A', mounted between the rails A, so as to rotate said spindle through an angle of ninety degrees each time a pin strikes a projection, and thereby cause the target to disappear and reappear alternately. 55

In order that the target may not be liable to turn when hit, it is held in position by suitable spring-retaining mechanism, which, as illustrated in Figs. 2, 5, and 6, consists of a spring-operated arm K, having a notch L in 60 its head adapted to engage and retain teeth or studs M, Figs. 2 and 6, on the projections H of the tappet-wheel and be pushed out of engagement by the pins J, which strike the beveled faces k^2 of said head. 65

The rod A' is fitted with a plurality of rows of pins, those in each row being arranged at different distances apart, and the rotation of said rod and consequent bringing into action of a differently-set row of pins is automatically effected by means of downwardly-projecting-fingers N at each end of the traveler B, engaging one of a series of cam-faces O, arranged on each end of the rod A', causing a partial revolution of the rod A' on each run 70 of the traveler. 75

In the modification illustrated in Fig. 7 the fingers N are curved to form cam-guides, while the cam-faces O, Fig. 1, are replaced by radial arms O', practically constituting a 80 reversal of the previously-described arrangement.

Q, Fig. 2, indicates guides on the under side of the traveler to insure the pins J contacting squarely with the projections H, and R a vertical guide in which the pivoted arm or grip D works when rounding the pulleys, 85 Fig. 4.

Briefly described, the operation is as follows: Motion being imparted to the endless wire or cord C, the traveler or carrier B will be reciprocated along the rails A, the tappet-arms H during the motion of the traveler or carrier being operated by the projections J upon the rod A' to give to the arbor or shaft 95 of the target F a quarter-turn upon each operation of the shaft. When the traveler reaches the ends of the rails, the rod A', as hereinbefore set forth, is given a partial turn 100

in order to bring a different set of projections J into position for use.

Having now particularly described and ascertained the nature of my said invention and 5 in what manner the same is to be performed, I declare that what I claim is—

1. An improved apparatus for operating moving targets on miniature ranges comprising a traveler, rails for supporting the traveler, a rotatable target mounted upon the traveler, means for intermittently rotating the target through an angle of approximately ninety degrees, so as to turn the same "edge on" and "face on" alternately, and yieldable 10 means supported independently of the target-operating means for retaining the target in its different positions, said yieldable means being operated by the target-operating means, as the latter is turned in order to momentarily release the target.

2. An apparatus for operating moving targets on miniature ranges, a traveler, means for operating the traveler, a spindle upon the traveler carrying a target and a tappet-wheel, 25 means for operating the tappet-wheel in order to partially rotate the spindle and thereby the target, and yieldable means for engaging the tappet to thereby normally maintain the target in a fixed position and operable by the 30 tappet-operating means to momentarily release the target.

3. In apparatus for operating moving targets on miniature ranges a traveler running on a pair of horizontal rails said traveler having a rotatable pivoted arm or grip, an endless traveling wire attached to said arm or 35

grip and a vertical guide for said arm or grip, substantially as specified and as illustrated.

4. An apparatus for operating moving targets on miniature ranges, a traveler, means 40 for operating said traveler, a target mounted upon the traveler and having a tappet-wheel, means for intermittently operating the tappet-wheel, teeth upon said tappet-wheel, and a spring-operated retaining-arm having a 45 notch adapted to engage said teeth.

5. In apparatus for operating moving targets on miniature ranges a rotatable rod mounted between a pair of rails said rod having a plurality of rows of pins thereon and 50 having a series of cam-faces at each end to engage fingers on each end of a traveler so as to partially revolve said rod on each run of the traveler substantially as and for the purposes specified and as illustrated. 55

6. An apparatus for operating moving targets on miniature ranges, a rotatable rod, a reciprocating traveler having a target, projections upon the rod arranged in sets, means connected with the target for operation by 60 said projections to turn the target as the traveler reciprocates, and means for turning said rod when the traveler reaches the opposite ends of its travel.

In testimony whereof I have hereunto set 65 my hand in presence of two subscribing witnesses.

JOHN WILLIAM PORTER.
